UNITED STATES PATENT OFFICE.

HARRISON B. WALTER, OF DANVILLE, ILLINOIS, ASSIGNOR TO NATIONAL FIBRE
BOX COMPANY, OF DANVILLE, ILLINOIS, A CORPORATION OF ILLINOIS.

FASTENING THE ENDS OF THE BINDING STRIP OR BAND WHICH PASSES AROUND
A BOX.

1,026,417.

Specification of Letters Patent. Patented May 14, 1912.

Application filed August 25, 1911. Serial No. 645,918.

To all whom it may concern:

Be it known that I, HARRISON B. WALTER, a citizen of the United States, residing at Danville, in county of Vermilion and State 5 of Illinois, have invented certain new and useful Improvements in Fastening the Ends of the Binding Strip or Band which passes Around a Box, of which the following is a specification.

10 My invention relates to an improvement in fastening the ends of the binding strip or band which passes around a box.

This invention is adapted more particularly for boxes which are capable of being 15 folded together, and the sides of which are provided with battens, to which the sides are connected, as well as the end members.

The object of the invention is to provide 20 a slot in a batten at each end of the box, whereby a tool can be inserted in the slot for 25 clenching the rivet or eyelet which is inserted through the ends of the band for fastening the ends of the band together, and to the body or one of the sides of the box.

25 The invention consists in certain novel features of construction and combinations of parts which will be hereinafter fully described and pointed out in the claim.

In the accompanying drawings, Figure 1 30 is a perspective view of the box; and Fig. 2 is an enlarged detail sectional view through the slotted batten and fastening means connecting the ends of the band to the body of the box.

35 A, represents the body of the box, which consists of four sides, each side having a batten 1 connected thereto, which battens are provided with beveled ends 2 for forming a mitered joint when the box is folded 40 together. A band 3, preferably of metal, passes around the body A of the box, and is connected thereto by means of nails 4 which are driven through the band and body into the battens, whereby the band and body are

securely fastened to the battens. One of 45 the battens 1 on each end of the box is provided with a slot 5, the ends of the bands 3 overlapping each other over the slotted portion of the battens. A rivet 6 is inserted through the ends of the band and through 50 the body A of the box, whereby the tool (not shown) can be inserted in the slot 5 for clenching the end of the rivet or eyelet 6 for fastening the ends of the band together and to the body of the box. It is the 55 object of the invention to use a tool which can be inserted in the slot for punching a hole through the ends of the band and body of the box, through which the rivet or eyelet can be placed, and then by the same tool, 60 clenching the rivet for fastening the ends of the band and body together. As any form of tool for this purpose can be used, I have not deemed it necessary to disclose any 65 particular form, as the tool forms no part of the present invention.

Having fully described my invention, what I claim as new and desire to secure by Letters Patent, is:—

The combination with the body portion of 70 a box and a frame to which the body portion is secured, said frame having an open slot in the edge to which the body portion is attached, of a band facing and encircling the 75 part of the body portion adjacent to the frame, the ends of the band overlapping each other over the open slot, and a rivet extending through the overlapped ends of the band, the body portion adjacent thereto, and into the slot in which latter its inner 80 end is upset.

In testimony whereof I affix my signature, in the presence of two witnesses.

HARRISON B. WALTER.
